ABSTRACT OF THE DISCLOSURE

Heteroaryloxy ethers of 1-(2-hydroxyethyl)-5-nitroimidazole are herein described. These compounds are potent anti-microbial agents. They are prepared by the reaction of a heteroaromatic alcohol with 1-(2-chloroethyl)-2-methyl-5-nitroimidazole in aprotic polar solvents in the presence of base and sodium or potassium iodide.

The present invention relates to a group of [2-(2-methyl-5-nitro-1-imidazolyl)ethyl]heteroaryloxy ethers of the general formula.

wherein R is a mono or binuclear heteroaromatic radical. The position of oxygen attachment to the carbon of the heteroaromatic is optional and mono and poly substitution pattern on the aromatic nucleus among halo, lower alkyl, and nitro substituents are likewise optional. The preferred heteroaromatic nuclei are pyridyl and benzo(b) pyridyl. Preferred embodiments of the pyridyl derivatives are those in which R is pyridyl and 2-bromo-3-pyridyl. Preferred embodiments of benzo(b)pyridyl are those in which R is 4-(8-chlorobenzo(b)pyridyl), and 8-(5-nitrobenzo(b)pyridyl), 8-(5,7-dichlorobenzo(b)pyridyl), and 8-(2-methyl-5,7-dichlorobenzo(b)pyridyl).

The compounds of the present invention are heteroaryloxy ether derivatives of 1-(2-hydroxyethyl)-5-nitroimidazole, which is described as a potent bactericidal agent in U.S. Pat. 2,994,061. The present compounds are prepared by the general method of Scheme I.

An aprotic polar solvent solution of 1-(2-chloroethyl)-2-methyl-5-nitroimidazole (*J. Med. Chem.*, 11, 370, 1968) and sodium or potassium iodide is added to a basic aprotic polar solvent solution of a heteroaromatic alcohol. Dimethylsulfoxide, dimethylformamide, dimethylacetamide, and acetonitrile are suitable solvents and alkali metal lower alkoxide salts and sodium hydride are suitable bases. Thus, a dimethylformamide solution of 1-(2-chloroethyl)-2-methyl-5-nitroimidazole and sodium iodide is added to a dimethylformamide solution of 3-hydroxypyridine and sodium ethoxide to form 2-methyl-5-nitro-1[2-(3-pyridyl-oxy)ethyl]imidazole.

2

The compounds of the present invention are useful in view of their anti-microbial activity. They are especially effective in inhibiting the growth of protozoa and bacteria.

Evidence of the anti-protozoal utility of the present compounds is obtained from standardized tests designed to determine the capacity of test compounds to inhibit the growth *Trichomonas vaginalis*. These tests are carried out in the following manner. A modified Diamond medium is prepared by mixing 1200 parts of trypticase (Baltimore Biological Laboratories), 600 parts of yeast extract (Difco), 300 parts of maltose, 60 parts of L-cysteine hydrochloride, 12 parts of L-ascorbic acid, 48 parts of dibasic potassium phosphate, 48 parts of monobasic potassium phosphate and 54,000 parts of distilled water. The pH is adjusted to 6.8 with 40% sodium hydroxide solution and 30 parts of agar (Baltimore Biological Laboratories) is incorporated. The mixture is boiled for one minute to dissolve the agar and is then sterilized in an autoclave. To 80 volumes of the resultant medium is aseptically added 20 volumes of sterile Dubos medium serum. The resultant medium is inoculated with 1% by volume of a 72 hour culture of *T. vaginalis*, whereupon 1 ml. of the inoculated medium is mixed with 10 mg. of test compound. The mixture is incubated anaerobically at 37° C. for 48 hours and then examined microscopically for the presence of motile trichomonads. If any are observed the compound is considered inactive. If no motile trichomonads are observed, 0.1 ml. of the incubated mixture is serially diluted and mixed with quantities of the inoculated medium sufficient to produce concentrations of 1000, 100, 10 and 1 micrograms of test compound per ml. and the resulting mixtures are incubated anaerobically as before at 37° C. for 48 hours and then examined microscopically for the presence of motile trichomonads. Controls are provided by concurrent incubations identical with the foregoing except for the absence of test compound.

Evidence of the antibacterial utility of the instant compounds is provided by standardized tests for their capacity to prevent the growth of *Bacillus subtilis*. In these tests, a mixture of 5 mg. of compound with 5 ml. of sterile nutrient broth is heated at 80° C. for 20 minutes, then cooled to around 25° C., and finally serially diluted and mixed with sufficient quantities of a mixture of sterile nutrient broth and 1% of a culture of *B. subtilis* to produce concentrations of approximately 400, 100, 25, and 6 mcgm. of compound per ml. The resultant mixtures are incubated for 20-24 hr. at 37° C. Controls are provided by concurrent incubations identical with the foregoing excepting that no compound is present. Activity is determined by gross examination; and potency is expressed as the minimum concentration, in mcgm. of compound per ml., at which no growth of the test organism is discernible.

The following examples are presented to further illustrate the present invention. They should not be construed as limiting it either in spirit or in scope. In these examples quantities are indicated in parts by weight unless parts by volume are specified, and temperatures are indicated in degrees centigrade (° C.). The relationship between parts by weight and parts by volume is the same as that existing between grams and milliliters.

EXAMPLE 1

3.72 parts of 1-(2-chloroethyl)-2-methyl-5-nitroimidazole and 3.0 parts of sodium iodide are dissolved in 40 parts by volume of dimethylformamide and the solution is added to a stirring mixture of 1.08 parts of sodium methoxide and 3.6 parts of 4-hydroxy-8-chloroquinoline in 25 parts by volume of dimethylformamide. The reaction mixture is refluxed under anhydrous conditions for 24 hours, cooled, diluted with 100 parts by volume of water. The product is extracted with chloroform and

the chloroform extracts are washed with dilute sodium hydroxide. The chloroform solution is dried over anhydrous sodium sulfate and then one-half of the solvent is removed by evaporation at reduced pressure. The addition of hexane causes precipitation of the product. The product is treated with decolorizing charcoal and recrystallized from chloroform-hexane. This procedure provides 2 - methyl-5-nitro-1-{2-[4-(8-chlorobenzo(b)pyridyloxy)ethyl]}imidazole, melting at 198-201°. The formula of this compound is

EXAMPLE 2

3.72 parts of 1-(2-chloroethyl)-2-methyl-5-nitroimidazole and 3.0 parts of sodium iodide are dissolved in 40 parts by volume of dimethylformamide and this solution is added to a stirring mixture of 1.10 parts of sodium methoxide and 3.81 parts of 5-nitro-8-hydroxyquinoline in 25 parts by volume of dimethylformamide. The reaction mixture is refluxed under anhydrous conditions for 24 hours, cooled, and diluted with 100 parts by volume of water. The product is extracted with chloroform and the chloroform is removed by evaporation at reduced pressure. The resulting solid is chromatographed on neutral silica gel. Development of the column is initiated with chloroform and the product is eluted with 2% ethanol in chloroform. The product is treated with decolorizing charcoal and recrystallized from chloroform-hexane. This procedure provides 2 - methyl - 5 - nitro-1-{2-[8-(5-nitrobenzo(b)pyridyloxy)ethyl]}imidazole, melting at 207.5-208°. The formula of this compound is

EXAMPLE 3

3.72 parts of 1-(2-chloroethyl)-2-methyl-5-nitroimidazole and 3.0 parts of sodium iodide are dissolved in 40 parts by volume of dimethylformamide and this solution is added to a stirring mixture of 1.25 parts of sodium methoxide and 4.28 parts of 5,7 - dichloro-8-hydroxy-quinoline in 25 parts by volume of dimethylformamide. The reaction mixture is refluxed under anhydrous conditions for 24 hours, cooled, and diluted with 100 parts by volume of water. The product is extracted with dilute sodium hydroxide. The chloroform is removed by evaporation at reduced pressure and the residual solid is chromatographed on neutral silica gel. Development of the column is initiated with chloroform and the product is eluted with chloroform. The product is treated with decolorizing charcoal and recrystallized from methanol-diethyl ether. This procedure provides 2-methyl-5-nitro-1 - {2 - [8(5,7-dichlorobenzo(b)pyridyloxy)ethyl]}imidazole, melting at 151.5-153°. The formula of this compound is

EXAMPLE 4

2.70 parts of 1-(2-chloroethyl)-2-methyl-5-nitroimidazole and 2.14 parts of sodium iodide are dissolved in 40 parts by volume of dimethylformamide and this solution is added to a stirring mixture of 0.85 parts of sodium

methoxide and 3.25 parts of 2-methyl-4-hydroxy-5,7-dichloroquinoline in 25 parts by volume of dimethylformamide. The reaction mixture is refluxed under anhydrous conditions for 24 hours, cooled, and diluted with 100 parts by volume of water. The product is extracted with chloroform and the chloroform extracts are washed with dilute sodium hydroxide. The chloroform is removed by evaporation at reduced pressure and the residual solid is chromatographed on neutral silica gel. Development of the column is initiated with chloroform and the product is eluted with chloroform. The product is treated with decolorizing charcoal and recrystallized from chloroform-hexane. This procedure provides 2-methyl-5-nitro-1-{2-[8 - (2 - methyl-5,7-dichlorobenzo(b)pyridyloxy)ethyl]}imidazole, melting at 124-125°. The formula of this compound is

EXAMPLE 5

3.72 parts of 1-(2-chloroethyl)-2-methyl-5-nitroimidazole and 3.0 parts of sodium iodide are dissolved in 40 parts by volume of dimethylformamide and this solution is added to a stirring mixture of 1.10 parts of sodium methoxide and 3.48 parts of 2-bromo-3-hydroxypyridine in 25 parts by volume of dimethylformamide. The reaction mixture is refluxed under anhydrous conditions for 24 hours, cooled, and diluted with 100 parts by volume of water. The product is extracted with chloroform and the chloroform extracts are washed with dilute sodium hydroxide. The chloroform is removed by evaporation at reduced pressure and the residual solid is chromatographed on neutral silica gel. Development of the column is initiated with benzene and the product is eluted with 5% ethanol in benzene. The product is treated with decolorizing charcoal and recrystallization from chloroform-hexane provides 2 - methyl - 5 - nitro-1-[2-(2-bromo-3-pyridyloxy)ethyl]imidazole, melting at 165-167°. The formula of this compound is

EXAMPLE 6

3.72 parts of 1-(2-chloroethyl)-2-methyl-5-nitroimidazole and 30 parts of sodium iodide are dissolved in 40 parts by volume of dimethylformamide and this solution is added to a stirring mixture of 1.10 parts of sodium methoxide and 1.91 parts of 3-hydroxypyridine in 25 parts by volume of dimethylformamide. The reaction mixture is refluxed under anhydrous conditions for 24 hours, cooled, and diluted with 100 parts by volume of water. The product is extracted with chloroform, then is precipitated by addition of hexane to the chloroform. The precipitate is treated with decolorizing charcoal and recrystallized from ethyl acetate-hexane. This procedure provides 2 - methyl-5-nitro-1-[2-(3-pyridyloxy)ethyl]imidazole, melting at 122-123°. The formula of this compound is

5
EXAMPLE 7

3.72 parts of 1-(2-chloroethyl)-2-methyl-5-nitroimidazole and 30 parts of sodium iodide are dissolved in 40 parts by volume of dimethylformamide and this solution is added to a stirring mixture of 1.10 parts of sodium methoxide and 1.19 parts of 4-hydroxypyridine in 25 parts by volume of dimethylformamide. The reaction mixture is refluxed under anhydrous conditions for 24 hours, cooled, and diluted with 100 parts by volume of water. The product is extracted with chloroform and it is precipitated by addition of hexane to the chloroform. The precipitate is treated with decolorizing charcoal and recrystallized from ethyl acetate-hexane. This procedure provides 2-methyl - 5 - nitro-1-[2-(4-pyridyloxy)ethyl]imidazole. The formula of this compound is

EXAMPLE 8

3.72 parts of 1-(2-chloroethyl)-2-methyl-5-nitroimidazole and 3.0 parts of sodium iodide are dissolved in 40 parts by volume of dimethylformamide and this solution is added to a stirring mixture of 1.10 parts of sodium methoxide and 1.19 parts of 2-hydroxypyridine in 25 parts by volume of dimethylformamide. The reaction mixture is refluxed under anhydrous conditions for 24 hours, cooled, and diluted with 100 parts by volume of water. The product is extracted with chloroform, then is precipitated by addition of hexane to the chloroform solution. The precipitate is treated with decolorizing charcoal and recrystallized from ethyl acetate-hexane. This procedure provides 2-methyl-5-nitro-1-[2-(2-pyridyloxy)ethyl]imidazole. The formula of this compound is

EXAMPLE 9

3.72 parts of 1-(2-chloroethyl)-2-methyl-5-nitroimidazole and 3.0 parts of sodium iodide are dissolved in 40 parts of volume of dimethylformamide and this solution is added to a stirring mixture of 1.10 parts of sodium methoxide and 3.48 parts of 3-chloro-4-hydroxypyridine in 25 parts by volume of dimethylformamide. The reaction mixture is refluxed under anhydrous conditions for 24 hours, cooled, and diluted with 100 parts by volume of water. The product is extracted with chloroform and the chloroform extracts are washed with dilute sodium hydroxide. The chloroform is removed by evaporation at reduced pressure and the residual solid is chromatographed on neutral silica gel. Development of the column is initiated with benzene and the product is eluted with 5% ethanol in benzene. The product is treated with decolorizing charcoal and recrystallization from chloroform-hexane provides 2-methyl-5-nitro-1-[2-(3-chloro-4-pyridyloxy)ethyl]imidazole. The formula of this compound is

6
EXAMPLE 10

3.72 parts of 1-(2-chloroethyl)-2-methyl-5-nitroimidazole and 3.0 parts of sodium iodide are dissolved in 40 parts by volume of dimethylformamide and this solution is added to a stirring mixture of 1.10 parts of sodium methoxide and 3.48 parts of 2-bromo-4-hydroxypyridine in 25 parts by volume of dimethylformamide. The reaction mixture is refluxed under anhydrous conditions for 24 hours, cooled, and diluted with 100 parts by volume of water. The product is extracted with chloroform and the chloroform extracts are washed with dilute sodium hydroxide.
